COMBINED KEY RING AND COIN HOLDER

Michael Dolas, 1164 Crestline Drive,
Santa Barbara, Calif. 93105

Filed July 15, 1974, Ser. No. 488,452

Term of patent 14 years

Int. Cl. D3—02

U.S. Cl. D87—1 R

Fig. 4

FIG. 1 is a top plan view of a combined key ring and coin holder showing my new design;

FIG. 2 is an edge view thereof;

FIG. 3 is a bottom plan view; and

FIG. 4 is a three-dimensional view.

I claim:

The ornamental design for a combined key ring and coin holder, as shown and described.
